6 Claims. (Cl. 126—116)

The invention relates to heating devices operated with liquid fuel (and intended more especially for use in motor vehicles), of the kind having a tubular combustion chamber into which a fuel-air mixture, delivered by a displacement blower, is fed through an inlet aperture, the displacement blower supplying all the air for combustion. In addition there is provided an ignition device surrounded by a tubular protective casing, the axes of the protective casing and the combustion chamber being substantially parallel.

Heating devices of this type can be of small dimensions and are stable in operation in respect of disturbances liable to originate from the effect of headwind on the exhaust gas. Another advantage of this construction is that it can be provided with long exhaust pipes, thus substantially reducing installation problems. For these devices combustion chambers have been developed comprising an annular space into which leads the pipe conducting the fuel-air mixture. In these combustion chambers, however, and particularly at temperatures below -10° C., the fuel-air mixture is difficult to ignite.

The present invention aims at providing a heating device which retains the advantages of the above-described known type of heater but which can be started easily even at low temperatures.

According to the invention the protective casing surrounding the ignition device is disposed inside the combustion chamber (which is preferably in the form of a cylindrical tube), and its axis is offset in relation to the axis of said chamber in such a manner that the distance between the part of the combustion chamber wall accommodating the fuel-inlet aperture and the protective casing of the ignition device is greater than the distance between the protective casing and the part of the combustion chamber wall which lies opposite to the inlet aperture.

On account of the off-setting of the protective casing of the ignition device, and notwithstanding the large quantity of air entering the combustion chamber from the displacement blower at high pressure as compared with other types of blowers, more of the fuel, first impinging against the wall of the combustion chamber, becomes deposited on to the protective casing, due to the barrier action of the wall of the combustion chamber, which, viewed from the inlet aperture, lies behind the protective casing.

In order to obtain adequate build-up of fuel round the protective casing, the distance between the part of the combustion chamber wall lying opposite the inlet aperture and the protective casing of the ignition device should be not more than 4 mm., and preferably less than 2 mm.

With regard to the offset location of the protective casing, the distance between the combustion chamber axis and the axis of the tubular protective casing should amount to at least one-fourth of the diameter of the inlet aperture for the fuel-air mixture. If the inlet aperture is not circular, this dimension should be determined by the diameter necessary to provide a circular aperture of the same cross-section as the non-circular inlet aperture. It is also of importance in a device according to the invention that between the protective casing and the combustion chamber wall at the narrowest part of the combustion chamber, a distance of at least $\frac{1}{2}$ mm., and preferably 1 mm., is pro-

2

vided so that the annular form of that part of the combustion chamber is not entirely lost, because in that case the flow conditions would be affected.

Experiments have shown that the delivery of the fuel on to the protective casing is also advantageously promoted if the axis of the inlet aperture forms with the axis of the combustion chamber an acute angle which preferably amounts to at most 70° , but to not less than 20° , while the point of intersection of said axes is nearer than the inlet aperture, to the exhaust gas pipe connected to the combustion chamber. A swirl plate may be provided in the part of the supply pipe for the fuel-air mixture directly before the inlet aperture.

Ease of ignition at low temperatures may further be increased by a sieve disposed inside the protective casing and lying, as viewed from the combustion chamber, behind a row of holes provided in the protective casing.

One example of a heating device according to the invention will now be described with reference to the accompanying drawings, which will reveal still further features and advantages of the invention.

In the said drawings, FIGURE 1 shows a heating device according to the invention in side elevation and partly in section, and

FIGURE 2 a section through the heating device shown in FIGURE 1, along the line II—II.

As can be seen in the heating device illustrated in FIGURE 1, a driving motor 3 in a casing 2 located at one side of a heater 1 drives a blower 4 to circulate air to be heated, and a displacement blower 5 which delivers combustion air and liquid fuel through the pipe 6 and a hollow screw 7 to a combustion chamber 8, in which a sparking plug 10 surrounded by a protective casing 9 is installed. The passage 11 for the hot gases of the burnt fuel lies inside the heat transmitter 1 and at its end near to the burner forms a part of the combustion chamber, and it extends rectilinearly to an exhaust gas outlet 12 to which an exhaust pipe may be connected.

The air to be heated passes through the inlet aperture 13 into the blower 4, and from the latter is delivered into the heating passage 14 which encircles the hot gas passage 11. In the air passage 14 the air flows to the outlet 17 over ribs 16 provided therein on a cylindrical surface 15, and then through a pipe (not shown) into the compartment of the vehicle which is to be heated.

In the cylinder 15 safety passages 18 and 19, which, as can be seen in FIGURE 2, extend, with other passages 20 and 21, parallel to the axis of the combustion chamber 8 and the hot gas passage 11, are intended to prevent the exhaust gases from entering the air passage 14 in the event of a leak developing in the passage 11.

As can also be seen from FIGURE 1, the sparking plug 10 and its casing 9 are formed as a unit with a screw-threaded body portion for screwing into an aperture in the combustion chamber. The casing 9 is offset in relation to the axis of the combustion chamber so that at the side of the combustion chamber opposite to the inlet 7 the wall of the casing 9 is close to the wall of the combustion chamber. At this point the clearance should not be more than 4 mm., and is preferably less than 2 mm.

An annular sieve may be fitted within the protective casing 9 but for clarity is not shown in the drawing. This sieve may be situated, as viewed from the combustion chamber 8, behind a row of holes 23 in the protective casing 9 and may extend to a point near to the sparking plug 10.

A swirl device in the form of a helix may be fitted inside the hollow screw 7 and may have approximately the form of a mincer spiral but substantially shorter, and this also is not shown in the drawing, for clarity.

As shown in FIGURE 1 the disposition of the inlet

mouth formed by the end of the hollow screw 7 is such that on the one hand part of it is in close proximity to the protective casing 9 but another part is at a greater distance therefrom than the part of the combustion chamber wall 24 nearest the protective casing 9. The greater spacing between the wall part 25 of the combustion chamber 8 which supports the inlet aperture and the casing 9 as compared with that between the part 24 of the combustion chamber wall lying opposite the inlet aperture and the casing 9 can also be clearly seen from FIGURE 2, 10 which also shows the moon-shaped cross-section of the combustion chamber which is a feature of the invention.

The invention is not restricted to the exemplary embodiment described, but may be modified and added to in various ways without departing from the scope of the invention as defined in the appended claims.

What I claim is:

1. A liquid fuel operated heating device comprising in combination:
  - a heat exchanger including means defining a first channel having a circular cross sectional area for combustion gases and means defining a second channel having an annular cross sectional area substantially surrounding said first channel for a heat transfer medium;
  - a burner having an outer wall coaxial and in direct communication with said first channel means, said outer wall having a fuel inlet aperture therein, a tubular protective casing disposed within said outer wall and having its axis offset with respect to the axis of said outer wall, the outer surface of said tubular casing and the inner surface of said outer wall defining an annular combustion chamber whereby the radial distance between the portions of the inner surface of said outer wall containing the fuel inlet aperture and the outer surface of said tubular casing is greater than the distance between the diametrically opposed portions of the inner surface of said outer wall and the outer surface of said tubular 40

casing respectively, and an ignition device disposed within said tubular casing;

a positive displacement blower for furnishing the total air and fuel necessary for combustion to said burner through a supply line communicating with said fuel inlet aperture; and

driving means for said positive displacement blower.

2. A heating device as claimed in claim 1 wherein the radial distance between the said diametrically opposed portions of the inner surface of said outer wall and the outer surface of said tubular casing is less than 4 mm.

3. A heating device as claimed in claim 1, wherein the distance between the combustion chamber axis and the axis of said tubular protective casing is at least one-fourth of the diameter of the fuel inlet aperture for the fuel-air mixture.

4. A heating device as claimed in claim 1, wherein between said protective casing and said outer wall at the narrowest point of the combustion chamber a spacing of 0.5 mm. to 1 mm. is provided.

5. A heating device as claimed in claim 1, wherein the axis of the fuel inlet aperture forms with the axis of the combustion chamber an acute angle, the point of intersection of the said axis being closer to said ignition device than to said means defining said first channel communicating with said combustion chamber.

6. A heating device as claimed in claim 5, wherein the angle between the axes of the combustion chamber and the fuel inlet aperture amounts to not more than 70°, and not less than 20°.
